(57) **CLAIM**

The ornamental design for a multipurpose bucket, as shown.

DESCRIPTION

FIG. 1 is a perspective view of a multipurpose bucket in accordance with the present invention;

FIG. 2 is a reduced side elevational view, the opposite side view being a mirror image thereof;

FIG. 3 is a reduced top plan view thereof;

FIGS. 4–7 are perspective, reduced side elevational, reduced top plan, and reduced end elevational views, respectively, of the interior bucket shown in FIG. 1;

FIGS. 8–11 are perspective, reduced side elevational, reduced top plan, and reduced end elevational views, respectively, of the main bucket shown in FIG. 1; and,

FIGS. 12–15 are perspective, side elevational, reduced top plan, and reduced end elevational views, respectively, of the wringer shown in FIG. 1.

The main and interior buckets and the wringer are shown separately for clarity of illustration only.
